TOOL FOR REMOVING SPIN-ON OIL FILTERS

William H. Loflin, 208 S. Olive St.,
Kermit, Tex. 79754

Continuation-in-part of abandoned design application Ser. No. 373,644, June 26, 1973. This application Sept. 8, 1975, Ser. No. 611,183

Term of patent 14 years

Int. Cl. D8—05

U.S. Cl. D8—29

FIG. 1

FIG. 2

FIG. 3

FIG. 4

FIG. 1 is a top view of the tool for removing spin-on oil filters;

FIG. 2 is a bottom view of the tool disclosed in FIG. 1;

FIG. 3 is a perspective view of the tool disclosed in FIGS. 1 and 2, which is drawn to a reduced scale. The broken line showing of an oil filter is for illustrative purposes only;

FIG. 4 is a side elevational view of the tool.

This is a continuation-in-part of design patent application Ser. No. 373,644 filed June 26, 1973, entitled "Tool for Removing Spin-On Oil Filters," now abandoned.

I claim:

The ornamental design for a tool for removing spin-on oil filters, substantially as shown and described.
